UNITED STATES PATENT OFFICE.

JOHN F. SCHLOEMER, OF LOS ANGELES, CALIFORNIA.

EGG-CASE FILLER.

Application filed June 2, 1926. Serial No. 113,129.

This invention relates to improvements in egg case fillers.

An object of this invention is to provide an improved egg case filler adapted to be used 5 in conjunction with the flat disclosed in my patent No. 1,588,624, patented June 15, 1926, so that a lock may be established between the flats and the filler, preventing any shifting or movement of the filler relatively to 10 the flat.

Another object of this invention is to provide an improved egg case filler of novel construction which provides for easy ventilation between one cell and another.

15 A further object of this invention is to provide an egg case filler which may be easily, quickly and cheaply constructed and easily and quickly assembled.

With the foregoing and other objects in 20 view which will be made manifest in the following detailed description and specifically pointed out in the appended claim, reference is had to the accompanying drawings for an illustrative embodiment of the invention, wherein:

Figure 1 is a partial top plan view of an egg case, illustrating the improved filler disposed therein,

Fig. 2 is a vertical section taken substantially on the line 2—2 of Fig. 1, and

Fig. 3 is a partial perspective view of the improved filler upon the flat.

Referring to the accompanying drawings wherein similar reference characters designate similar parts throughout, the walls of the egg case are generally designated at 10, in which there are disposed a plurality of flats arranged one above the other and indicated at 11 and 12. The flats disclosed are 40 similar to those disclosed in my aforementioned patent and have egg receiving recesses 13 formed on their upper sides, these recesses being so arranged that they will be disposed at the centers of the bottoms of the cells 45 provided by the filler. There are also formed recesses 14 upon the flat, which recesses are on the upper sides of the flat and are so arranged as to be disposed beneath the corners of the cells formed by the filler. As 50 these recesses are formed by embossing the flat, they form projections 15 on the under side of the flat.

The improved filler is primarily designed to be used in conjunction with the flat above described. It consists of a plurality of parallel longitudinal partitions 16, which are

crossed by and intersected by transverse partitions 17. The longitudinal partitions 16 have vertical slots 18 formed therein extending from the top edges downwardly and the 60 transverse partitions 17 have slots 19 extending from their bottom edges upwardly. These partitions are preferably formed of pasteboard or the like and are assembled together in a manner very similar to the conventional filler. At the intersections of the 65 partitions or at the corners of the cells defined thereby the partitions have projections or extensions 20 formed on their bottom edges and these projections or extensions are 70 adapted to enter the recesses 14 on the flat 12 on which the filler is positioned. The top edges of the longitudinal and transverse partitions at their points of intersection or at the corners of the cells are cut away, as indicated at 21, forming recesses which are 75 adapted to receive the projections 15 formed on the under side of the flat which is positioned on top of the filler. In this manner it will be appreciated that the engagement 80 between the filler and the two flats above and below forms a type of lock which prevents the filler from shifting laterally relatively to the flats. Because of this construction the flats which fit snugly within the egg case assist in keeping the fillers in their proper 85 position therein and prevent any sliding toward the side of the case which might occur if the case should be tilted or turned over on its side. Centrally of the side walls of each 90 cell the top and bottom edges are cut away, as indicated at 22, forming passages above and below the bottom and top flats respectively, permitting free circulation of air 95 from one cell to another so that all of the cells are well ventilated.

From the above described construction it will be appreciated that a novel filler is provided which is primarily designed to be used in connection with the flat which is disclosed 100 in my aforementioned patent, and which is advantageous in that the filler at all points of intersection of the partitions is lockingly engaged by the flat to hold it in proper position in an egg case.

105 It will be understood that various changes in the detail of construction may be made without departing from the spirit and scope of the invention as defined by the appended claim.

I claim:

110 In an egg case, two parallel flats, each flat

being embossed to form depressions on its upper side and projections on its lower side, and a filler formed of intersecting longitudinal and transverse partitions, the bottom edges of the partitions presenting projections adapted to enter the depressions on the upper side of the lower flat, the upper edges of the partitions being cut away to form recesses adapted to receive the projections on

the bottom surface of the upper flat, said depressions, projections and recesses being locked at the corners of the cells defined by the partitions, the top and bottom edges of the filler intermediate the corners of the cells being cut away to provide for ventilation. 10

In testimony whereof I have signed my name to this specification. 15

JOHN F. SCHLOEMER.
